UNITED STATES PATENT OFFICE.

ALANSON P. BRUSH, OF DETROIT, MICHIGAN.

FOUR-CYCLE INTERNAL-COMBUSTION ENGINE.

1,187,606.

Specification of Letters Patent. Patented June 26, 1916.

Application filed February 1, 1915. Serial No. 5,419.

To all whom it may concern:

Be it known that I, ALANSON P. BRUSH, a citizen of the United States, residing at Detroit, in the county of Wayne and State of Michigan, have invented a certain new and useful Improvement in Four-Cycle Internal-Combustion Engines, of which the following is a full, clear, and exact description.

This invention is an improvement in the type of four-cycle internal combustion engines in which each piston, on its suction and explosion strokes, compresses air, and which is provided with means whereby said compressed air is admitted to the cylinder above the piston during a brief period while the piston is completing its explosion stroke and beginning its exhaust stroke, and during another brief period while the piston is completing its suction stroke and is beginning its compression stroke.

One object of the invention is to insure that a rich charge of the compressed explosive mixture shall be in contact with the spark plug when the spark passes, so that the charge shall certainly be ignited.

Another object is to increase the efficiency of the engine.

Another object is to more completely scavenge the engine on the exhaust stroke; And another object is to effect these results without the use of mechanically operated valves to control the flow of the compressed air.

The invention consists in the construction and combination of parts shown in the drawing and hereinafter described and definitely pointed out in the appended claim.

In the drawing Figure 1 is a longitudinal vertical sectional view of a two-cylinder internal combustion engine which embodies the invention; Fig. 2 is a vertical sectional view of one of the cylinders in a plane at right angles to the crank shaft and passing through the exhaust port; Fig. 3 is a vertical sectional view in a plane at right angles to the crank shaft through the inlet port and charged segregating chamber of one of the cylinders.

Referring to the parts by letters, A A represent the engine cylinders; B B represent the pistons thereof; C C represent air compression chambers, one associated with each cylinder. Each of these chambers has an ordinary air admitting check valve c . As shown, the lower part of each cylinder serves as an air compression chamber; but

any air-tight chamber having a check valve and constructed and connected with the lower half of the cylinder so that the down stroke of the piston will compress the air therein will serve the purpose. But having determined to utilize the lower half of the cylinder as the air compression chamber instead of, for example, the crank case, the lower end of each cylinder is closed as by the bottom wall a . The piston rod b , which is connected with each piston, passes out through a stuffing box F. The usual crank shaft D is connected with the piston rods by connecting rods H.

The head plate E is preferably, but not necessarily, common to all of the cylinders of which the engine is composed, and is secured thereto. It contains cored out inlet and outlet ports e , e' and carries the inlet valves J and exhaust valves K. In this head plate is a charge segregating chamber M. This is at its lower end in open communication with the upper end of the cylinder; and the inlet port e communicates with the upper end of this chamber M,—the inlet valve J being arranged to permit or prevent the flow of the explosive mixture from the inlet port into this charge segregating chamber M.

K' represents a by-pass, one of which is associated with each cylinder. It is connected at one end with the air compression chamber of said cylinder, and at its other end is likewise connected with said cylinder by means of the port a' at a point such that the piston on its down stroke will pass this port whereby this by-pass will place the air compression chamber below the piston in open communication with the cylinder above the piston.

N represents the spark plug. One of these for each cylinder is carried by the head plate, and projects into the charge segregating chamber, as shown in Fig. 3.

The operation of the described engine is as follows: When a piston is moving upward it draws air through the check valve c into the associated air compression chamber. On the suction down stroke the explosive mixture is drawn in past the valve J into the charge segregating chamber and thence into the cylinder. As the piston nears the lower end of its stroke it passes and uncovers the port a' , whereupon, and so long as this port remains uncovered, compressed air will flow through the by-pass

into the cylinder above the piston. This air will more or less freely mix with the explosive mixture in the cylinder, but will not mix much with the explosive mixture which has remained in the charge segregating chamber. When, however, the piston moves upward on its compression stroke it will compress this mixture of the explosive charge and air, and the result will be a much higher compression than if the cylinder contained only the explosive mixture drawn in through the inlet port. The gas which is in the charge segregating chamber, and especially in the end thereof adjacent to the spark plug, will be much richer than that part of the charge which is below this point. Therefore, when the spark passes there is the greater certainty that the charge will be ignited. When as a result the piston goes down on its explosion stroke it will again compress air in the air compression chamber. When the piston passes the port a^3 , this compressed air will rush into the cylinder above the piston. To a considerable extent it will mix with the exploded gases in the cylinder and dilute them, so that as a result when the piston moves on its exhaust stroke the exhaust gases in the cylinder, as distinguished from those in the charge segregating chamber, will be more completely exhausted than those with the ordinary construction. When the piston now goes down on its suction stroke, and the explosive mixture is drawn into the charge segregating chamber, this incoming mixture will drive out the exhaust gases which were in the charge segregating

chamber, and therefore, as before stated, this chamber will contain a very rich mixture when the piston completes its next compression stroke.

Having thus described my invention, what I claim is:

In a four-cycle internal combustion engine, the combination of the cylinder, a removable head plate therefor containing a charge segregating chamber which extends upward from the lower face of said head plate, said head plate containing a valve controlled inlet port which discharges directly into the upper end of said charge segregating chamber, and a valve controlled exhaust port which communicates through the lower face of said head plate with the upper end of the cylinder, a spark plug carried by said head plate and projecting into said charge segregating chamber, a compressed air chamber which has an air admitting check valve and is in open communication with that part of the cylinder which is below the piston therein, and a by-pass having its lower end connected with said air compressing chamber, and having its upper end connected with said cylinder by means of a port which passes through the cylinder wall at a point such that the piston will pass and uncover the same when it has nearly reached the end of its down stroke.

In testimony whereof, I hereunto affix my signature in the presence of two witnesses.

ALANSON P. BRUSH.
